UNITED STATES PATENT OFFICE

HANNAH M. SCHULER, OF GALESBURG, ILLINOIS

AUTOMOBILE SCREEN

Application filed October 12, 1926. Serial No. 141,126.

This invention relates to window guards and more particularly to a screen adapted to be mounted in covering relation to a window of an automobile and prevent bees and other insects from entering the vehicle.

One object of the invention is to permit the screen to be securely but removably applied to the body portion of a door of a vehicle without interfering with opening or closing of the glass closure panel.

Another object of the invention is to provide the screen with a guarded passage through which a hand may be passed in order to grasp the handle of a door and open it.

The invention is illustrated in the accompanying drawing, wherein

Figure 1 is a perspective view showing the interior of the forward portion of a closed automobile having the improved screen applied to its door;

Fig. 2 is a sectional view taken on the line 2—2 of Fig. 1, and

Fig. 3 is an enlarged sectional view taken on the line 3—3 of Fig. 1.

In Fig. 1, the screen, which is indicated in general by the numeral 1, has been shown applied to the door 2 of a closed automobile, but it will be understood that the screens could also be applied to the side and rear windows or windshield opening. The screen consists of a sheet of woven wire 3 preferably of copper or other rust-proof metal and has its margins protected by a binding 4 formed of oilcloth or other suitable fabric. Sockets 5 are secured in openings formed in the binding and serve not only as sockets but also as fasteners to assist the stitching 6 in firmly retaining the binding in place about the woven sheet 3. A hand opening 7 is formed

in the woven wire sheet 3 adjacent one lower corner thereof and has its margins protected by a binding 8 which is similar to the binding 4 and preferably secured by stitches 9. A closure flap 10 which is also oilcloth and of sufficient size to close the opening 7 is secured

adjacent its upper end by a line of stitching 11 and adjacent its lower corners carries sockets 12 which are smaller than the sockets 5 and adapted to be snapped into engagement with studs 13 sewed to the binding 8 adjacent 50 its lower corners. It will, therefore, be seen that the closure flap may be normally held shut but can be easily released and swung upwardly to an open position when it is desired to pass a hand through the opening 7 55 and grasp a latch operating handle projecting outwardly from a vehicle door. The screen is of sufficient length and width to completely cover the window opening of a door to which it is to be applied and in order 60 to securely hold it in place there has been provided studs 14, the threaded shanks 15 of which are screwed into the body of the door. The studs are disposed in spaced relation to each other about the margins of the 65 window opening of the door and each is provided with a head 16 to fit into a cooperating socket 5, as shown in Fig. 3. A groove 17 is formed in the head 16 so that the shank 15 may be turned into the body of the door 70 through the medium of a screw driver and a collar 18 is fitted upon the shank in contacting engagement with the head so that the shank may not be screwed too far into the door. It will thus be seen that the screen may 75 be very easily applied to a door and will be very securely but releasably held in place. The screen will serve to very effectively exclude insects from an automobile and will also to some extent exclude dust. When use 80 of the screens are not necessary, they may be removed and stored in the automobile.

Having thus described the invention, I claim:

A screen comprising a sheet of screening 85 of greater dimensions than an opening to be covered thereby, a binding for the margins of said sheet consisting of a strip folded longitudinally and disposed about the sheet in straddling relation to the margins thereof 90

with side portions overlapping opposite faces of the sheet, fastener members passed through the side portions of the binding and the marginal portions of the sheet overlapped thereby and serving to secure the binding of the sheet, and companion fastener members adapted to be mounted about the borders of an opening and releasably engageable with the first-mentioned fastener members to removably secure the sheet in covering relation to the opening.

In testimony whereof I affix my signature.

HANNAH M. SCHULER. [L.S.]
